GUARD FOR DOORWAYS

Louis J. Goran, Brooklyn, N. Y., assignor to Truscon Steel Company, Youngstown, Ohio, a corporation of Ohio

Application November 20, 1933, Serial No. 698,890
Renewed July 6, 1937

3 Claims. (Cl. 20—19)

The present invention relates to that type of door for steam-ship piers and the like, in connection with which a barrier or guard must be employed at times to prevent persons passing through the doorway when the door is opened and may be said to be of the general type disclosed in an application for patent filed by me October 23, 1933, Serial No. 694,896.

The object of the present invention is to provide a guard or barrier that is supplemental to the door structure and is so constructed and equipped that it can be carried by the same and thus deposited out of the way where it will occupy very little space and that space being otherwise unusable, or it can be left in an operative position across the lower portion of the doorway while the door is elevated or moved to open position.

In the accompanying drawings:—

Figure 1 is an inside elevation of a pier door constructed in accordance with the present invention.

Figure 2 is a vertical sectional view on the line 2—2 of Figure 1.

Figures 3, 4, 5 and 6 are detail sectional views respectively on the lines 3—3, 4—4, 5—5 and 6—6, of Figure 1.

Figure 7 is a view diagrammatic in its character illustrating the relation of the parts when the door is in its completely closed position.

Figure 8 is a similar view, but showing the door partly open.

Figure 9 is a view showing the door completely opened with the barrier stored thereby.

Figure 10 is a view showing the barrier or guard in active position with the door partially opened and indicating in dotted lines how it may be completely opened.

The door structure as a whole may be of the type shown in the patent to Morgan, No. 1,789,189, dated January 13, 1931, and therefore it is believed to be unnecessary to go into details as to the structure and the operating mechanism therefor. It is believed therefore sufficient to explain that a framed doorway is provided that is adapted to be closed by a vertically movable door. This door includes an upper leaf 11 hinged at its upper end, as shown at 12, and adapted to swing inwardly and upwardly from a vertical closed position to a substantially horizontal opened position. A lower leaf 13 is slideable between a position below the upper leaf to a position behind the same, and thence to be swung with the upper leaf to said horizontal or substantially horizontal position.

The operating means for the door includes a shaft 14 carrying chain wheels 15, over which pass chains 16 connected to the lower ends of lifting levers 17. These lifting levers are guided in tracks 18 that are arranged vertically on opposite sides of the doorway and are turned rearwardly at their upper ends, as illustrated at 19. The lower leaf 13 is pivotally journaled as indicated at 20 to intermediate portions of the lifting levers.

As shown particularly in Figure 3, the lower leaf 13 when in its lowered position, has its sides engaged in vertical guideways 21, so as to prevent the lateral displacement of the leaf when in its active position.

For the purpose of providing a barrier across the lower portion of the doorway to prevent ingress and egress therethrough when the door is opened, a guard member 22 is provided, which in the present construction is a unit in addition to the complete door structure. This guard may be in the form of a light frame 23 constructed of aluminum, providing panels in which suitable netting 24 may be placed. This netting, as illustrated in detail in Figure 5 is held by suitable hooks 25. The upper edge of the barrier member may have a rounded hand rail portion 26. As shown in Figure 3 the end bars of the guard rail frame are extended as shown at 27 and have offset flanges 28 that are slidably engaged in the guideways 21. These guideways preferably terminate at the top of the lower door leaf 13.

The guard member 22, it will be noted, is a unit or entity separate from and in addition to the door structure including the lower leaf, and when the lower leaf is in its active position, this guard member is alongside the inner side of the same. Means are provided for detachably coupling the guard member 22 to the lower leaf 13. This means in the embodiment shown, includes a rock shaft 29 journaled in the lower leaf and carrying a plurality of inwardly and upwardly inclined latches 30 which are adapted to detachably engage the undersides of inset portions 31 of the guard rail plate 26. An upstanding lever 32 affords convenient means for operating the rock shaft, and a spring 33, connected to the rock shaft, urges the same in a direction to project the latches inwardly, and therefore into operative relation to engage the guard member.

It is believed that the operation of the structure can now be made clear. When the door is closed, the latches 30, carried by the lower leaf, will engage under the hand rail or upper end of

the guard member 22. If the door is operated in the normal manner, when the lower leaf is elevated, it will carry the guard member with it, as indicated in Figure 8, and a continued movement of the door to fully opened position carries the guard member to a point above the door, where it is out of the way and occupies space that is ordinarily unusable. It will thus be seen that for normal purposes, the guard moves with the door and in no manner interferes with the latter's movement. If, however, it is desired to place an obstruction across the lower part of the doorway to prevent ingress or egress of persons, then the guard member 22 is unlatched from the lower leaf by swinging the lever 32 outwardly, carrying the latches 30 to positions where they will be disengaged from the guard. If now the door is operated, the guard remains across the lower part of the doorway, while the door moves in its normal manner to any position between a partly and completely opened situation. Whenever it is desired to remove the guard, it is only necessary to lower the door, whereupon the latches will automatically re-engage the guard and thus connect it to the lower leaf.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim is:

35 1. In combination, a doorway including guide members, a door section movable in said guide members, and a doorway guard adapted to be left in lowered position between said guide members when the said door section is raised or to

be carried with the door section when the same is elevated, means offset laterally at the ends of said guard for substantially embracing the ends of said door section and having flange portions located within said guide members whereby the guard is guided by the same means which guides the door section when both are elevated and also positions the guard in the doorway when the door alone is elevated, and means for detachably interconnecting the guard and door section. 10

2. In combination, a doorway including guide means at the opposite sides thereof, a door section slidably in said guide means, means for counterbalancing said door section arranged at one side of the normal plane of said door section, and a guard located at the opposite side of the normal plane of said door section, and means for connecting and disconnecting the guard from said door section whereby the guard may be left in a lowered position between said guide means across the doorway or may be elevated with said door section, said guard member having side frame portions extending across the ends of the door section and having offset terminal portions 25 engaging in said guide means.

3. In combination, a doorway including guide means, a door slidably in the guide means, and a doorway guard normally offset to one side of the door and having means extending across the edges of said door section for entering said guide means whereby the guard and door may move in the same guideway, means for connecting and disconnecting the guard and door for simultaneous or separate movement, said guard comprising a frame provided with a hand rail at the top thereof, said hand rail defining the upper limit of the guard. 35
